DESIGN FOR A WHEEL BALANCE WEIGHT

James R. Dailey, Kokomo, Ind., assignor to
Turner Manufacturing Company, Kokomo,
Ind., a corporation of Indiana

Application August 4, 1947, Serial No. 140,695

Term of patent 7 years

(Cl. D14—30)

To all whom it may concern:

Be it known that I, James Robert Dailey, a citizen of the United States of America, residing at Kokomo, Indiana, in the county of Howard and State of Indiana, have invented a new, original, and ornamental Design for a Wheel Balance Weight, of which the following is a specification, reference being had to the accompanying drawings, forming a part thereof.

Fig. 1 is a top plan view of a wheel balance weight embodying my new design;

Fig. 2 is a front elevational view thereof;

Fig. 3 is an end elevational view thereof.

Fig. 4 is a vertical transverse sectional view thereof on the line 4—4 in Fig. 2; and Fig. 5 is a bottom plan thereof.

I claim:

The ornamental design for a wheel balance weight, substantially as shown.

JAMES R. DAILEY.
